UNITED STATES PATENT OFFICE.

PHILIP K. SHAFFER, OF REDLANDS, CALIFORNIA, ASSIGNOR OF ONE-HALF
TO SARAH S. CARNAHAN, OF SAME PLACE.

NON-CLOGGING WATER-GATE.

SPECIFICATION forming part of Letters Patent No. 629,725, dated July 25, 1899.

Application filed April 27, 1899. Serial No. 714,723. (No model.)

To all whom it may concern:

Be it known that I, PHILIP K. SHAFFER, residing at Redlands, in the county of San Bernardino and State of California, have invented 5 a new and useful Non-Clogging Water-Gate, of which the following is a specification.

The object of this invention is to provide a water-gate for flumes which will be free from any danger of clogging with moss or leaves 10 or any other trash that may be carried along by the water.

My invention relates to gates for side outlets from a flume or pipe; and it consists in 15 a rearwardly-flaring wing extending from the front of the gate and having a top extension to form a closure above the outlet of the gate.

The invention can be applied in the original construction of the gate and can also be applied as an attachment to gates already in 20 use.

My invention includes the parts and combinations hereinafter described and claimed.

The accompanying drawings illustrate my invention in two modes of its application.

25 Figure 1 is a perspective view of my improved water-gate in the side of a flume, a fragment of which is shown. Fig. 2 is a plan section of the same on line 2 2, Fig. 4. Fig. 3 is a section on line 3 3, Fig. 4. Fig. 4 is a 30 vertical section on line indicated by 4 4, Fig. 2. Fig. 5 is a view of a form in which the wing is an attachment made separate from the slide-frame and adapted to be applied to flume-gates already in use. Fig. 6 is a section on line 35 6 6, Fig. 5, the slide being removed.

A indicates the side of the flume, which is provided with a water-outlet B.

C indicates the slideway, which is preferably made of sheet metal nailed to the flume 40 with tacks c. In the drawings two forms of slideway are shown. In Figs. 5 and 6 the slideway C is made of a sheet of metal bent at its edges, as at 1 2, to form the grooves of the slideway, and the slide D is fitted in the 45 slideway. This is a common construction and no claim is made thereto.

E indicates a sheet-metal wing fastened at the forward edge of the gate and bent to flare rearward therefrom into the flume and bent 50 obliquely, as at e, at the upper free edge and

rearward corner to form a closure above the outlet of the gate. By preference the slideway is formed integral with the wing, as shown in Figs. 1, 2, 3, and 4, in which views the metal sheet is shown bent at one edge, as 55 at 2', to form one edge groove of the slideway, and is bent intermediate its edges, as at 1', to form the other edge groove of the slideway, and is then bent away from the slideway to form the wing or shield E', and 60 the top edge thereof and rear free corner are bent obliquely and toward the slideway to form a cover over the space between the wing and slideway.

In practice the slideway-plate C of Fig. 5 65 or C' of Fig. 1, as the case may be, is fastened to the flume-wall A by the tacks c, and in case of the form shown in Fig. 5 the wing E is then fastened to the wall by tacks e', so that the edge of the bent portion e will be 70 against the face of the slide D when the same is in place.

I have provided a combined slideway and shield, as illustrated in Figs. 1, 2, 3, and 4, in which the metal sheet of which the slideway and the shield or guard are formed is bent first to form one groove 2' of the slideway at one edge of the sheet. The sheet is then bent intermediate its edges, as at 1', to form the other groove of the slideway, and is then bent 80 flaringly, as at E', to project rearward from the front edge, beyond the water-outlet, and the upper free corner then is bent diagonally, as at e", to bring the upper edge into the path of or against the slide when the same is inserted in the slideway. If the edge is bent to stand normally in the path of the slide, it will be sprung away from the slideway when necessary to admit the slide. 85

3 indicates holes through the wing E' to allow tacks c to be driven through the plate to secure the front edge of the slideway to the flume-wall. The sheet forming the slideway is perforated between the bends, as at B, to form the water-outlet over which the gate 95 slides.

In practical operation the water flowing down the flume will be deflected away from the water-outlet B, and the trash and other material will be prevented from entering the 100

outlet. The top pieces *e* and *e*'' prevent the debris from falling down between the wing and the slideway.

In Figs. 1 and 5 large arrows show the direction in which the water flows.

The water behind the outlet will be comparatively still, and the water will flow to the outlet B free from anything that can clog the outlet.

10 Now, having described my invention, what I claim as new, and desire to secure by Letters Patent, is—

15 1. A water-gate for the side of a flume provided with a rearwardly-flaring wing with a top extension to form a closure above the outlet of the gate.

20 2. The combination with a flume-side gate, of a sheet-metal shield fastened to the gateway at the front edge thereof and bent to flare rearwardly therefrom and bent obliquely at the upper free corner to form a closure above the outlet of the gate.

25 3. In a water-gate, a combined slideway and shield composed of a metal sheet bent at one edge to form one groove of the slideway and bent intermediate its edges to form the

other groove of the slideway, and perforated between such bends to form the water-outlet, such sheet being bent flaring from the slideway rearward of the intermediate bend to 30 form a shield for the water-outlet and bent diagonally at the top to form a closure above the water-outlet.

4. A combined slideway and shield for a water-gate comprising a metal sheet bent at 35 one edge to form one groove of a slideway and having an intermediate bend to form the other groove of the slideway and perforated between the bends with a hole for the water-outlet and with other holes for nails or other 40 fasteners, the sheet beyond the intermediate bend being bent, flaring from the slideway rearwardly and bent diagonally at its top to form a closure above the water-outlet and being perforated near the intermediate bend in 45 line with the holes for the fasteners on that side of the slideway.

PHILIP K. SHAFFER.
